(57) **CLAIM**

The ornamental design for a bow carrying case, as shown and described.

DESCRIPTION

FIG. 1 is a perspective view of a bow carrying case, illustrated with arrows, showing my new design;

FIG. 2 is a perspective view of the bow carrying case, illustrated without arrows, showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing of arrows in the drawings is for the purpose of illustrating environmental structure of the bow carrying case that form no part of the claimed design.
